CHILD'S BOOT

Edward R. Barron, Gloversville, N. Y.

Application October 4, 1949, Serial No. 5,294

Term of patent 14 years

(Cl. D7—4)

To all whom it may concern:

Be it known that I, Edward R. Barron, a citizen of the United States, residing at Gloversville, county of Fulton, and State of New York, have invented a new, original, and ornamental Design for a Child's Boot, of which the following is a specification, reference being had to the accompanying drawing, forming a part thereof, in which—

Fig. 1 is a perspective view of a child's boot, showing my new design; and

Fig. 2 is a rear elevational view.

I claim:

The ornamental design for a child's boot, as shown.

EDWARD R. BARRON.
